UNITED STATES PATENT OFFICE.

FRANK W. SCHROEDER, OF BEMIDJI, MINNESOTA.

EGG-TESTER.

1,161,793.

Specification of Letters Patent. Patented Nov. 23, 1915.

Application filed November 16, 1914. Serial No. 872,373.

To all whom it may concern:

Be it known that I, FRANK W. SCHROEDER, a citizen of the United States, residing at Bemidji, in the county of Beltrami and State 5 of Minnesota, have invented a new and useful Improvement in Egg-Testers, of which the following is a specification.

This invention relates to improvements in egg testers, of that character in which the 10 eggs are tested without having to remove them from the trays, in which they are usually held when packed in delivering trays and shipping cases or crates. It is desirable in vending eggs to test them as they are 15 being sold to the customer, and prove that they are good and to remove any defective ones.

My invention provides means whereby the trays can be removed bodily one at a time, 20 while loaded with eggs and placed in my improved tester, whether the trays are of the usual one or two dozen size. This saves a great deal of time and produces the most advantageous results.

25 In addition to this mode of operation, my invention provides means whereby each tray when inserted in my improved tester, will automatically turn on the light which is used for testing purposes, and when removed, automatically shut off the light, thus 30 economizing to the greatest extent in the use of electric current, which is employed for illuminating purposes.

In addition to these features, my invention 35 provides greater simplicity and less expensive construction, and greater effectiveness in use than in prior devices.

In the accompanying drawing forming part of this specification, Figure 1 is a front 40 elevation of my invention, partly broken to expose part of the inner construction; Fig. 2 is an end elevation on a reduced scale, and Fig. 3 is a cross section taken on the line X-X of Fig. 1.

45 In the drawing A indicates the body of a casing, which is closed on four sides and formed with a floor 2 and a transverse vertical partition 3, thus providing two chamber compartments 4 and 5, the upper end 50 of the casing being left open. The compartment 5 is smaller than the compartment 4, the object being to provide suitable areas for accommodating trays holding one or two dozen of eggs. The front wall 6 is 55 formed with an opening 7, entering the compartment 4, and with an opening 8 entering

the compartment 5, said openings being of suitable size and shape to assist in admitting the trays into the compartments while in horizontal position.

The inwardly facing surfaces of the longitudinal sides of each compartment have secured thereto suitable longitudinal supports 9, which rest with their upper surfaces substantially level with the lower edges of the openings 7 and 8, so as to produce suitable means for slidably supporting the trays or filler compartments carrying the eggs. Placed in the lower portion of each compartment are electric lamps such as 10, 65 there being a socket such as 11 secured to the floor 2 in each compartment for holding the lamp therein. These lamps in the two compartments are connected in multiple with an electric circuit, suitable conductors 65 such as 12 leading through the rosette 13 on the side of the structure, being provided for electrically illuminating the lamps.

One side of the circuit of each lamp has inserted therein a suitable switch B, said 80 switches being located near the ends of each compartment in the path of the trays, which are inserted in each compartment, so as to close the circuits containing the lamps when the trays loaded with eggs are placed in the 85 device to be tested. Each switch consists of a base 14 carrying a substantially immovable terminal piece 15, and a flexible terminal piece 16, to which the ends of the circuit including the lamp are adapted to be attached. 90 Normally the flexible terminal 16 remains out of contact with the terminal 15, but when the tray is placed in one of the compartments its inner end is adapted to strike against a button or head piece 17 carried 95 on the free end of the flexible terminal and close the flexible terminal against the immovable terminal 15, thus completing the circuit and illuminating the lamp placed below the tray of eggs.

100 The compartment 4 being larger than the compartment 5, one compartment is adapted to test trays containing more eggs than the other. The distance the switch B is placed in compartment 5 from the front portion 105 is not as great as in compartment 4, and the inner portion of compartment 5 is closed by a horizontally disposed plate 18, the switch for compartment 5 being mounted near the forward edge of said plate, so that 110 the flexible terminal 16 will close against the immovable terminal 15, when the tray or

filler of eggs to be tested is slid fully into compartment 5 through the opening 8. The dimensions and sizes of the compartments may be varied to suit the dimensions 5 or sizes of the trays and fillers of eggs to be tested, and any number of compartments may be employed within the spirit of my invention, it being obvious that for each compartment a complete equipment such as 10 above described is applied thereto. The sizes and shapes of the openings 7 and 8 can also be varied to admit any size or design of tray, which it is desired to test, it being preferable although not always essential 15 that the shape and size of the openings be closed by the tray when the latter is fully inserted in the device in readiness to be tested. A cleat 19 is placed back of each switch to which the base 14 is secured to support the switch in a substantial manner.

The upper portion of the structure is provided with a hood C, which is constructed with a partition 20, which coincides with the partition 3 in the body, thus dividing 25 the hood into compartments, which correspond and register with the compartments in the body. Each compartment in the hood is provided with a sight opening 21 surrounded by a shield 22, so as to shield the 30 eyes of the observer. The hood is secured upon the body, such as by hinges 23 and locked in closed position by the hook 24. When it is desired to adjust the lamps or any of the parts of the apparatus, the hood 35 can be swung back out of the way, and access had to the compartments in the body. The lower front portion of the hood is also provided with openings 25 and 26, which correspond respectively with the openings 40 7 and 8 and serve to complete passages entering the compartments to admit trays thereinto. In use the trays filled with eggs can be lifted one at a time, without touching the eggs, from the egg crate or other container and placed in the tester. As each tray is placed in the tester the lamp in the compartment in which the tray is placed is illuminated automatically until the tray is withdrawn.

50 At the inner ends of the side supports 9 in each compartment a shock absorber in the form of a bumper 27 made of rubber or other suitable material is secured against which the inner end of the tray strikes when 55 the switch has been closed to prevent eggs being broken, should a tray be inserted too vigorously or carelessly.

After testing, the trays can be delivered to the customer or placed back in the container or crate. This operation can be performed very quickly, it being obvious that a large number of eggs are tested simultaneously, which is much speedier than in devices where a single egg at a time is tested, 65 or where it is necessary to remove the eggs

from the trays or fillers, in order to test them. The handling of the eggs as employed with my improved apparatus also avoids the danger of breaking eggs in testing.

70 The apparatus is economical in the use of electric current, the lights only being illuminated while the trays remain fully inserted in the tester. Any source of electric current can be employed, such as derived from an 75 ordinary lighting circuit or from batteries. The apparatus is also adapted for use with trays of any suitable construction, the term "tray" where used throughout this specification and in the claims following, being intended to cover any construction of tray or 80 filler section such as is commonly employed for delivering or shipping eggs.

Having described my invention, what I 85 claim as new and desire to protect by Letters Patent is:

1. An egg tester, comprising, in combination with an egg tray, two coöperating elements, one a body and the other a hood coupled together and forming a chamber, 90 one of said parts being passaged to assist in admitting said tray into said chamber, and said hood having a sight opening through which the eggs held by said tray can be viewed, illuminating means positioned 95 below said tray in said chamber and a switch connected with said illuminating means to cause its illumination when closed, said switch being supported in position so that the inner end of said tray will strike against 100 and close the switch when the tray is fully inserted in said chamber.

2. An egg tester, comprising, in combination with an egg tray, two coöperating elements, one a body and the other a hood 105 coupled together and forming a chamber, one of said parts being passaged to assist in admitting said tray into said chamber, and said hood having a sight opening through which the eggs held by said tray 110 can be viewed, illuminating means positioned below said tray in said chamber, a switch connected with said illuminating means to cause its illumination when closed, said switch being supported in position so that the inner end of said tray will strike against 115 and close the switch when the tray is fully inserted in said chamber and a shock absorber in the path of said tray when the latter is inserted in said chamber and closes 120 said switch.

3. An egg tester, comprising, in combination with an egg tray, two coöperating elements, one a body and the other a hood hinged together and forming a chamber, 125 said parts being passaged to assist in admitting said tray into said chamber, and said hood having a sight opening through which the eggs held by said tray can be viewed, an electric lamp positioned below said tray in 130

said chamber, a switch connected with said electric lamps to cause their illumination when closed, said switch being supported in position so that the inner end of said tray 5 will strike against and close the switch when the tray is fully inserted in said chamber, supports at the sides of said chamber for said tray as it is inserted therein and shock absorbers at the inner ends of said supports 10 against which the inner end of the tray is adapted to strike.

4. An egg tester, comprising, in combination, egg trays, two coöperating elements, one a body and the other a hood coupled 75 together and divided to form a plurality of chamber compartments, one of said parts being passaged to assist in admitting one of said trays into each of said compartments,

and said hood having eight openings, one entering each compartment, independent 20 illuminating means in each compartment positioned below the tray therein and a switch connected with each illuminating means in position, so that the inner end of the tray strikes against and closes a switch automatically 25 and causes the illuminating means to be illuminated, whereby the illuminating means is operated in either compartment when a tray is placed therein.

In testimony whereof, I have signed my 30 name to this specification in the presence of two subscribing witnesses.

FRANK W. SCHROEDER.
